DESIGN FOR A SKIRT

Mark Sigoda, New York, N. Y.

Application June 6, 1940, Serial No. 92,841

Term of patent 3½ years

To all whom it may concern:

Be it known that I, Mark Sigoda, a citizen of the United States, residing in New York city, in the county of New York and State of New York, have invented a new, original, and ornamental Design for a Skirt, of which the following is a specification, reference being had to the accompanying drawings, forming part thereof.

Fig. 1 is a front view of a skirt showing my design,

Fig. 2 is the rear view thereof, and

Fig. 3 is an enlarged fragmentary view of the skirt shown in Fig. 1, illustrating the trim of the pleating and embroidery in detail, a unit and a half being shown by the dot and dash lines.

I claim:

The ornamental design for a skirt, substantially as shown and described.

MARK SIGODA.
